CLAIM

The ornamental design for a backless bench, substantially as shown and described.

DESCRIPTION

FIG. 1 is a frontal perspective view showing a backless bench according to my new design, the dashed lines indicating seat structure not forming a part of my design;

FIG. 2 is a right side elevation view thereof, the left side elevation being identical;

FIG. 3 is a front elevation view thereof, the dashed lines indicating seat structure not forming a part of my design;

FIG. 4 is a rear elevation view thereof, the dashed lines indicating seat structure not forming a part of my design;

FIG. 5 is a top plan view thereof, the dashed lines indicating seat structure not forming a part of my design;

FIG. 6 is a bottom plan view thereof, the dashed lines indicating seat structure not forming a part of my design;

FIG. 7 is a perspective view showing a second embodiment of a backless bench according to my new design, the dashed lines indicating seat structure not forming a part of my design;

FIG. 8 is a right side elevation view thereof, the left side elevation being identical;

FIG. 9 is a front elevation view thereof, the dashed lines indicating seat structure not forming a part of my design;

FIG. 10 is a rear elevation view thereof, the dashed lines indicating seat structure not forming a part of my design;

FIG. 11 is a top plan view thereof, the dashed lines indicating seat structure not forming a part of my design; and,

FIG. 12 is a bottom plan view thereof.
